Primary Examiner — Antoine D Davis

(74) Attorney, Agent, or Firm — Banner & Witcoff, Ltd.

(57) **CLAIM**

The ornamental design of a digital tire pressure and tread depth gauge, as shown and described.

DESCRIPTION

FIG. 1 is a top, front, right perspective view of a digital tire pressure and tread depth gauge showing my new invention; FIG. 2 is a top plan view thereof; FIG. 3 is a right side elevation view thereof; FIG. 4 is a left side elevation view thereof; FIG. 5 is a bottom plan view thereof; FIG. 6 is front view thereof; and, FIG. 7 is rear view thereof.

The broken line showing of structural features is included for the purpose of illustrating non-claimed subject matter and forms no part of the claimed design.
